UNITED STATES PATENT OFFICE.

JEAN HUBERT LOUIS DE BATS, OF ZELIENOPLE, PENNSYLVANIA, ASSIGNOR TO NEW PROCESS METALS CORPORATION, OF WILMINGTON, DELAWARE, A CORPORATION OF DELAWARE.

CARBONIZING-FURNACE.

1,333,796.

Specification of Letters Patent. Patented Mar. 16, 1920.

Application filed August 19, 1918. Serial No. 250,463.

To all whom it may concern:

Be it known that I, JEAN HUBERT LOUIS DE BATS, a resident of Zelienople, in the county of Butler and State of Pennsylvania, 5 have invented a new and useful Improvement in Carbonizing-Furnaces, of which the following is a specification.

This invention relates to carbonizing furnaces and its object is to provide a 10 furnace for this purpose whereby all of the articles or pieces subjected to its action receive a uniform heat and a uniform carbonizing effect.

According to the usual methods of carbonizing iron and steel articles, the articles 15 are packed in charcoal or other carbonizing material in a closed container, and said container is placed in a suitable heating furnace and subjected to such temperature as 20 will cause carbon gases to be evolved from the carbonizing material, and which gases penetrate and deposit carbon on the metal articles. When carbonizing small articles or pieces, a number thereof are packed in 25 the carbonizing material in a single container, and, as a consequence, those nearest the outside of the container receive the greatest degree of heat, or are subjected to the heat for a longer time and are, therefore, 30 carbonized to a greater degree than those near the center of the container.

The purpose of my invention is to overcome the above objection, and to this end the furnace, which is a combined furnace and 35 container, is made rotatable and movable relative to the source of heat, so that all parts of the furnace chamber or container are brought into the same relation to the 40 source of heat, and each of the articles in said container or drum are subjected to the same temperature, and, therefore, to the same carbonizing conditions.

The accompanying drawings illustrate a 45 convenient embodiment of the invention. In said drawings Figure 1 is a longitudinal central section through the furnace; Fig. 2 is a transverse section on the line 2--2, Fig. 1, showing the condition in the drum while stationary; and Fig. 3 is a similar view 50 showing the condition as the drum rotates.

The container or furnace comprises a drum 1 having heads 2 closing its ends and provided on its inside with a refractory lin-

ing 3, such as refractory brick or mortar, backed by a layer of heat insulating material 55 4, such as "kieselguhr." The drum is constructed to be substantially hermetically sealed to exclude air, and the articles or pieces to be treated, and the carbonizing material, are inserted therein and removed 60 therefrom through a suitable door or doors 5 in the head or heads of the drum and which also are so constructed as to make a substantially air tight closure, and also are provided on their inner faces with a refractory member 3^a backed by a layer of 65 heat insulating material 4^a.

This drum is provided with bands 6 and is mounted upon two sets of rolls 7 which contact with said bands and rotatably support the drum. The rolls 7 are secured to longitudinal shafts 8 mounted in bearings on a suitable foundation, and one or both of which is positively driven from any suitable source. The drawings merely show a 70 belt pulley 9 secured to one of the shafts 8 as a suitable means for imparting rotation to the drum. The drum is rotated either by frictional contact of the driven rolls 7 with the bands 6 but, if desired, one 75 or more of the driven rolls and one or more of the bands engaged thereby may be toothed so as to secure a positive rotation of the drum.

The heat may be applied to the drum in any 80 suitable way, such for instance, as providing the same with an interior longitudinal heating flue or flues, preferably a central flue 10 provided with a refractory lining 11 and having its ends partially closed by the 85 annular refractory blocks 12 and 13, the latter of which forms a rotatable joint with the stack or chimney 14, provided with a damper 15. The heat may be applied to the flue in any suitable way, such as by means 90 of a gas burner 16 arranged to project the flame into the opposite end of the flue, as shown in Fig. 1, or connecting to said end of the flue a suitable coal or other furnace, or by mounting the drum in the chamber 100 of a suitable furnace, such as one of the usual carbonizing furnaces in which containers are placed. To prevent the products of combustion from passing too rapidly through the flue 10 and to spread the flame 105 and cause it to contact with the walls of the

flue, said flue is provided with a plurality of perforated baffles or transverse barriers 17, of refractory material.

The articles or pieces to be treated are indicated at 20 embedded in carbonizing material in the drum. The annular space in the drum is not completely filled with such pieces and carbonizing material, but preferably is filled only about half full, as indicated in Fig. 2, so that during the rotation of the drum the said pieces are moved around in the annular space in the drum and are moved in the carbonizing material, as indicated in Fig. 3. Since the drum rotates continuously, all portions of the heating chamber are brought into the same relation to the source of heat, and said heating chamber and its contents are heated to a uniform degree, as a result of which all of the articles or pieces are carbonized to the same degree. The tumbling of the articles in the drum agitates the carbonizing material so that the heat will more readily permeate and be uniformly conducted through the same; and also results in bringing new particles of carbonizing material into contact with the articles or pieces being treated.

The carbonizing material may be of the usual kind, but preferably will be graphite in a finely divided state, such as known as graphite "float." Preferably also, the articles or pieces will be preliminarily heated above the critical temperature to open up their pores, before placing the same in the

carbonizing drum, as described and claimed 35 in my application of even date herewith, Serial No. 250,462.

The apparatus illustrated obviously can be modified within wide limits.

What I claim is:—

1. A carbonizing container or furnace comprising a rotatably mounted hermetically closed drum constructed to receive the carbonizing material and the pieces to be carbonized, said drum being provided with an 45 interior flue, means for applying heat to said flue, and means for rotating said drum.

2. A carbonizing muffle or furnace comprising a rotatably mounted hermetically closed drum constructed to receive carbonizing material and the pieces to be carbonized, said drum being provided with a central longitudinal flue, means for applying heat to said flue, and means for rotating said drum. 50

3. A carbonizing muffle or furnace comprising a rotatably mounted hermetically closed drum constructed to receive carbonizing material and the pieces to be carbonized, said drum being provided with a central 60 longitudinal flue, means for applying heat to said flue, baffles in said flue, and means for rotating said drum.

In testimony whereof, I have hereunto set my hand.

JEAN HUBERT LOUIS DE BATS.
